(57) **CLAIM**

The ornamental design for a mobile device game controller substantially as shown and described.

DESCRIPTION

FIG. 1 is a perspective view of a mobile device game controller, showing my new design in a state that the mobile device game controller is open;

FIG. 2 is a top plan view thereof;

FIG. 3 is a perspective view thereof;

FIG. 4 is a bottom view thereof;

FIG. 5 is a side elevation view thereof;

FIG. 6 is a perspective view of the mobile device game controller, showing my new design in a state that the mobile device game controller is closed;

FIG. 7 is a top plan view thereof;

FIG. 8 is a perspective view thereof;

FIG. 9 is a bottom view thereof;

FIG. 10 is a side elevation view thereof;

FIG. 11 is a rear elevational view thereof; and,

FIG. 12 is a front elevation view thereof.
